US0D1036662S

(12) **United States Design Patent** (10) **Patent No.:** **US D1,036,662 S**
(45) **Date of Patent:** ** **Jul. 23, 2024**

(54) **TIP CAP AND DISINFECTING UNIT**

- (71) Applicant: **Becton, Dickinson and Company**, Franklin Lakes, NJ (US)
- (72) Inventors: **Paul P. Marici**, Piscataway, NJ (US); **Richard Timmers**, Westwood, NJ (US); **Ulas Kemal Ayaz**, Glen Ridge, NJ (US); **Paul Tarsia**, Ringwood, NJ (US)
- (73) Assignee: **Becton, Dickinson and Company**, Franklin Lakes, NJ (US)
- (**) Term: **15 Years**
- (21) Appl. No.: **29/845,626**
- (22) Filed: **Jul. 8, 2022**

(57) **CLAIM**

The ornamental design for a tip cap and disinfecting unit, as shown and described.

DESCRIPTION

FIG. 1 is an isometric view of a tip cap and disinfecting unit attached to a syringe;

FIG. 2 is a top view of the tip cap and disinfecting unit of FIG. 1 attached to a syringe;

FIG. 3 is a bottom view of the tip cap and disinfecting unit of FIG. 1 attached to a syringe;

FIG. 4 is a left side view of the tip cap and disinfecting unit of FIG. 1 attached to a syringe;

FIG. 5 is right side view of the tip cap and disinfecting unit of FIG. 1 attached to a syringe;

FIG. 6 is a rear view of the tip cap and disinfecting unit of FIG. 1 attached to a syringe; and,

FIG. 7 is a front view of the tip cap and disinfecting unit of FIG. 1 attached to a syringe.

The broken lines in the drawings illustrate portions of the tip cap and disinfecting unit and form no part of the claimed design.

1 Claim, 7 Drawing Sheets
